ILLUMINATED SPIRIT LEVEL

Filed April 1, 1929

UNITED STATES PATENT OFFICE

AUGUST J. ELLISON, OF DETROIT, MICHIGAN

ILLUMINATED SPIRIT LEVEL

Application filed April 1, 1929. Serial No. 351,489.

The present invention pertains to a novel illuminated spirit level for use by bricklayers, carpenters, etc. Much difficulty and eye strain are suffered by these workers when 5 working in dark places, and it is to relieve this condition that the device is particularly designed.

Accordingly a spirit level of more or less ordinary construction is fitted with a flash 10 light adapted to illuminate the sight or sights thereof at will. In the preferred embodiment, a single flash light is slidably mounted on the stock or body of the level and may thus be shifted to the particular sight that is to be 15 read.

The invention is fully disclosed by way of example in the following description and in the accompanying drawings, in which—

Figure 1 is a side elevation of the device; 20 Fig. 2 is a plan view thereof;

Fig. 3 is a section on the line 3—3 of Fig. 2; Fig. 4 is a plan view, partly in section, of a modification;

Fig. 5 is a longitudinal section thereof; 25 and

Fig. 6 is a section on the line 6—6 of Fig. 5.

Reference to these views will now be had by use of like characters which are employed to designate corresponding parts throughout.

In Figures 1, 2 and 3 is shown a spirit level 30 including an illuminated stock or body 1 preferably made of metal and of a frame like character. The stock 1 carries a pair of spaced sights 2 and 3 containing spirit tubes 35 4 and 5. The tubes 4 are perpendicular to the tubes 5 so that the level may be used for testing either horizontals or perpendiculars.

In one of the longitudinal edges of the stock 1 is formed a dovetail groove 6 throughout the length of the stock as shown more clearly in Fig. 3. A slide 7 is movable along the stock by reason of its dovetail rib 8 which fits in the groove 6. On the slide 7 is mounted a flash light 9 having a lamp 10

15 with a hood 11 and a switch button 12. It will now be apparent that the flash light 9 may be moved to whichever sight is in use and the latter illuminated by actuation of the switch button 12.

50 In the modification shown in Figs. 4, 5,

and 6, the stock 20 has a pair of sights 21 and 22 containing spirit tubes 23 and 24 respectively perpendicular to each other. Between the sights 21 and 22, the stock 20 is formed with a cavity 25. The sights include 55 rings 26, and the walls 27 of the cavity 25 as well as the rings are apertured in alignment as at 28 to afford communication between the cavity and the sights.

In the cavity is laid a flash light 29 having 60 in its ends lamps 30 and 31 directed towards the sights 21 and 22 respectively. The flash light which is also provided with a pair of switch buttons 32 for separately operating the lamps.

The top of the cavity is closed by a cover plate 33 suitably secured to the stock as shown in Figs. 5 and 6. This plate is formed with a pair of slots 34 permitting sliding movement of stems 35 passed therethrough 70 and secured to the switch buttons 32. Thus, the switch buttons are radially operable from the outer surface of the plate 33.

Although specific embodiments of the invention have been illustrated and described, it will be apparent that various alterations in the details of construction may be made without departing from the scope of the invention as indicated by the appended 75 claims.

What I claim is:—

1. An illuminated spirit level comprising a stock, a plurality of sights and spirit tubes carried thereby, said stock having a longitudinal groove along said sights, a slide 85 having a rib received in said groove, and a flash light carried by said slide.

2. An illuminated spirit level comprising a stock, a plurality of sights and spirit tubes carried thereby, said stock having a longitudinal groove at an edge thereof and along said sights, a slide having a rib received in said groove, and a flash light carried by said slide.

In testimony whereof I affix my signature. 95
AUGUST J. ELLISON.
